L. DOSTAL

ROLL OF ROLLING MILLS

Filed Feb. 14. 1921

*Inventor
L. Dostal,
By Marks & Clark
Attys.*

UNITED STATES PATENT OFFICE.

LEO DOSTAL, OF KLAUNO, CZECHOSLOVAKIA.

ROLL OF ROLLING MILLS.

Application filed February 14, 1921. Serial No. 444,931.

(GRANTED UNDER THE PROVISIONS OF THE ACT OF MARCH 3, 1921, 41 STAT. L., 1313.)

To all whom it may concern:

Be it known that I, LEO DOSTAL, a citizen of the Republic of Czechoslovakia, and residing at Kladno, Czechoslovakia, have invented certain new and useful Improvements in the Rolls of Rolling Mills (for which I have filed applications in Austria April 7, 1919, Patent No. 80,819; Germany, April 7, 1919, Patent No. 329,839; England, July 6, 1920; Poland, May 12, 1920; Czechoslovakia, April 15, 1920), of which the following is a specification.

The necks or journals of the rolls of rolling mills are usually made in one piece with the roll body, that is to say, of the same material as the latter. It would, however, be a desirable thing to make the necks of material that is more resistant to frictional wear than the bearing.

Moreover necks cast in one piece with the roll are very liable to break off, especially those of cast iron rolls, and they must be welded on or cast on, with consequent unreliable weak places at the weld or joint.

This drawback is obviated by making the necks separate of materials of high tenacity. Hitherto such necks have been fixed in the roll bodies by screwing or shrinking in, but with this kind of fixing the necks become loose owing to the lack of initial fixing stress.

According to the present invention the necks are fitted with an easy fit into the roll body and the fixing is effected by means of axial tie-members which by reason of the manner of fixing them in place their length and consequent higher degree of elasticity generate an elastic and permanent fixing stress.

One embodiment of this invention is illustrated by way of example in the accompanying drawing, in which is shown a longitudinal section of the improved roll.

The necks or journals *b* are fixed separate into the roll body *a*, so that the body *a* and the neck *b* can be made of different materials, for instance, the roll body may be made of a chill casting and the neck of wrought steel. The neck may have its qual-

ity improved or it may be hardened before it is fitted into the roll body, without the entire roll having, for this reason, to be subjected to the heat treatment, so that stresses due to the hardening cannot arise in the roll body.

The two necks *b* are pressed axially into the roll by means of one or more tie-members *c*. The ends of the tie-members are closed at *d* by riveting, shrinking or the like.

By riveting the tie-members while hot, the other parts being cool, all the parts are drawn together, and an elastic and permanent fixing stress is produced.

The necks *b* are fitted conically or cylindrically into the body *a*.

A sleeve *e* may be cast into the roll body *a* for the purpose of providing a better transmission of the pressure.

Having now described my invention, what I claim as new and desire to secure by Letters Patent is:—

1. In a roll for a rolling mill, the combination of an axially perforated roll body, axially perforated roll necks separate from said body, having extensions fitted into the ends of the axial perforation of said body, and a tie rod extending through the axial perforations of said necks and the axial perforation of said body, whereby said necks are held firmly in said body.

2. In a roll for a rolling mill, the combination of an axially perforated roll body, axially perforated roll necks separate from said body, having extensions fitted into the ends of the axial perforation of said body, axially perforated sleeves of metal on said extensions, and a tie rod extending through the axial perforations of said necks and said sleeves and the axial perforation of said body, whereby said necks are held firmly and resiliently in said body.

In testimony whereof I have signed my name to this specification.

ING. LEO DOSTAL.
